UNITED STATES PATENT OFFICE.

RICHARD E. JONES, OF GLEN OLDEN, PENNSYLVANIA, ASSIGNOR TO JONES COLD STORE DOOR COMPANY OF WASHINGTON COUNTY, A CORPORATION OF MARYLAND.

REFRIGERATOR-DOOR HINGE.

No. 822,279.

Specification of Letters Patent.

Patented June 5, 1906.

Application filed July 2, 1904. Serial No. 215,128.

To all whom it may concern:

Be it known that I, RICHARD E. JONES, a citizen of the United States, residing at Glen Olden, in the county of Delaware and State of Pennsylvania, have invented a new and useful Improvement in a Refrigerator-Door Hinge, of which the following is a specification.

This invention relates generally to hinges, and more particularly to a hinge specially adapted to be used upon refrigerator, dust-proof, and air-tight doors.

The object of the invention is to provide a hinge for refrigerator, dust-proof, and air-tight doors and which can be regulated as the occasion requires in order to make a perfectly tight fit of the door against the casing; and with this object in view my invention consists, essentially, in the employment of a long flat bar pivotally connected at its rear end to a casting attached to the door-frame or wall and connected at its forward end to a casting connected to the outer face of the door adjacent the center of the same, the intermediate portion of said bar passing through a guide attached to the door adjacent the rear or pivot end.

The invention consists also in the employment of a spring between the said bar and the door and a regulating or set screw working through the guide and bearing upon the bar for the purpose of increasing or decreasing the pressure upon the door, the regulating or set screw to have a jam-nut to prevent its working loose.

The invention consists also in certain details of construction hereinafter fully described, and pointed out in the claims.

In the drawings forming a part of this specification, Figure 1 is an elevation showing a compartment the door of which is hung upon hinges constructed in accordance with my invention. Fig. 2 is a horizontal sectional view of the hinge. Fig. 3 is a detail perspective view of the bar. Fig. 4 is a view of the guide. Fig. 5 is a perspective view of the bow-shaped spring. Figs. 6 and 7 are views of the castings. Fig. 8 is a sectional view of the casting shown in Fig. 7.

Referring to the drawings, A indicates a wall of a cold-storage compartment, and B the door in the same, which parts may be of the usual or any improved construction.

C indicates a casting rigidly secured to the door-frame or wall or refrigerator, and D is a casting rigidly connected to the outer face of the door adjacent the central vertical line of said door. The casting C is provided with the parallel horizontal apertured ears C', and the casting D is also constructed with parallel horizontal apertured ears D'.

E indicates the long flat bar enlarged at each end, as shown at E' in Fig. 3, each enlarged end having a vertical bore E², through which the bolts E³ are adapted to be passed, said bolts passing through the apertured ears and connecting the bar E to the castings. The bar E passes through a box-loop or guide F, which is made of iron or any suitable metal the same as the castings C and D and bar E, said box-loop or guide being rigidly connected to the outer face of the door adjacent its rear or pivot end, as most clearly shown in Fig. 2. The opening in this box-loop or guide is considerably wider than the thickness of the bar, and in practice I prefer to make that portion of the bar which rests in the guide considerably thicker than the other portions of the bar, as most clearly shown at E⁴, the curved or swelled face of said bar being arranged outwardly, and between the inner face of the bar and the rear wall or the guide of the door proper, if preferred, I interpose a bow-shaped spring G, the central portion of which bears against the guide or door and the ends against the bar, as most clearly shown in Figs. 1 and 2, and is kept in place by a projection or guide P, engaging a slot in spring S, or by a bolt. H indicates a regulating screw or bolt passing through the front wall of the loop or guide and bearing upon the swelled face of the bar. The casting D being secured near the longitudinal center of the door allows the spring G, bearing on the bar E, to force the heel or hinge edge of the door in against the frame; but as it is desirable to regulate this pressure and not force the door in too tight I employ the screw H. By tightening the screw H the heel or hinge edge of the door is drawn, by means of the guide F, toward the bar E, and this relieves the packing of some of the pressure, and by loosening the screw H the spring G is permitted to force the door in against the frame. By proper adjustment of the screw H the same pressure is obtained on the

hinge edge of the door as on the fastener side, and the door fits uniformly all around. By means of this regulating-screw and spring and the bar constructed and arranged as 5 herein shown and described I am able to maintain the proper pressure upon the door, so that a tight fit can be always obtained, and if any of the parts should wear or swell so as to interfere with the perfect fit of the 10 door such wear or swell can be compensated for by regulating the screw.

Having thus fully described my invention, what I claim as new, and desire to secure by Letters Patent, is—

15 1. A hinge of the kind described comprising castings secured respectively to a door and a door-frame, a bar pivotally connected to the castings, a guide carried by the door through which the bar loosely passes, a spring 20 carried by the guide and adapted to bear on

the inner face of the bar, and a screw working through the outer side of the guide and adapted to bear on the outer face of the bar.

2. A hinge comprising the castings adapted to be attached to the door and frame, a 25 box-loop or guide adapted to be attached to the door, a bar passing through the guide and pivotally connected at its opposite ends to the castings, that portion of the bar resting in the guide being thicker than the other portions, 30 and a bow-shaped spring arranged within the guide and bearing upon the inner face of the bar, and a regulating-screw working through the outer side of the box-loop or guide and adapted to bear against the swelled face of 35 the bar for the purpose set forth.

RICHARD E. JONES.
